UNITED STATES PATENT OFFICE.

EDGAR J. CHANDLER, OF EVERETT, WASHINGTON.

NUT-SPLITTER.

1,069,528.

Specification of Letters Patent.

Patented Aug. 5, 1913.

Application filed January 14, 1913. Serial No. 742,017.

To all whom it may concern:

Be it known that I, EDGAR J. CHANDLER, a citizen of the United States, residing at Everett, in the county of Snohomish and State of Washington, have invented new and useful Improvements in Nut-Splitters, of which the following is a specification.

The invention has for its object the provision of a tool particularly designed for removing nuts or burs from bolts, rods or like fastenings when it becomes practically impossible to remove the same in the ordinary way.

When a nut has become fixed upon a bolt or rod by corrosive action it becomes necessary to split the same in order to remove it and this is usually attended with vexation and requires the services of two operators, the one to hold a support beneath the nut while the other holds the chisel and delivers a blow thereon.

The present invention provides a tool which will enable the work of cutting a nut from a bolt, rod or other fastening by a single operator with comparative ease and despatch, since the tool embodies a support and chisel and may be held in one hand of the operator while a hammer grasped in the other hand may be used to deliver a blow upon the chisel to split the nut.

A further purpose of the invention is the provision of a tool which may be easily adapted to nuts of different sizes so that the work of removing a nut from a bolt may be effected in a rapid manner and with comparative ease without requiring the services of an assistant either to deliver a blow upon the chisel or to hold the hammer or like device against the nut to receive the force of the blow when the chisel is struck.

Figure 1 is a view in elevation of a tool for removing a nut from a bolt, rod or other fastening, showing the same in operative position. Fig. 2 is a front view of the tool, the hammer head being in vertical section. Fig. 3 is a top view of the tool, the outer portion of the handle being broken away. Fig. 4 is a horizontal section on the line $\alpha-\alpha$ of Fig. 1. Fig. 5 is a detail perspective view of the connection by means of which the handle is adjustably secured to the hammer head.

Corresponding and like parts are referred to in the following description, and indicated in all the views of the drawing, by the same reference characters.

The tool embodies a hammer head 1 and a chisel 2, the hammer head being attached to a handle 3 in any manner. The hammer head may be of any construction and the handle 3 may be attached thereto in any way. The chisel 2 has a stem 4 which constitutes a guide to direct the chisel in its movements and to hold it in proper place upon the hammer head. The stem 4 preferably constitutes a part of the chisel, the latter being located in advance of the stem. The hammer head is formed with an opening 5 to receive the stem 4, said opening being contracted near its upper end to form an inner shoulder 6, which receives the end thrust of an expansible helical spring 7 mounted upon the stem 4 and confined thereon by means of a nut 8 threaded upon the inner or lower end of the stem. The nut 8 is relatively long to admit of adjustment so as to vary the tension of the spring 7. In the preferable construction two stems 4 are provided, the one being a duplicate of the other and each being arranged to operate in an opening 5 formed in the hammer head 1 and each having a spring 7 and nut 8. The stems 4 are connected at their upper ends to each other and to the chisel 2. The provision of a pair of stems 4 insures holding the chisel in a given position with reference to the hammer head. The chisel occupies a position midway between the stems 4 so that the projecting end of the bolt or rod 9 may pass through the space formed between the upper ends of the guide stems when the tool is fitted to the nut 10 to be cut from the part 9.

When it becomes necessary to remove the nut from a bolt, rod or like part 9 by splitting the same the tool is arranged substantially as indicated in Fig. 1, that is with the hammer head 1 beneath the nut 10 and the chisel above said nut with its edge in line with the center of the bolt opening. The spring 7 exerts a downward pull upon the stem and chisel and holds the latter in engagement with the nut. The handle 3 is grasped by one hand of the operator and the other hand is supplied with a hammer or other tool for delivering one or more blows upon the chisel 2 to split the nut, which when cleft may be easily removed.

From the foregoing description, taken in connection with the accompanying drawing, the advantages of the construction and of the method of operation will be readily ap-

parent to those skilled in the art to which the invention appertains, and while I have described the principle of operation of the invention, together with the device which I 5 now consider to be the best embodiment thereof, I desire to have it understood that the device shown is merely illustrative, and that such changes may be made when desired as are within the scope of the claims 10 appended hereto.

In order to provide a tool that may be conveniently used in all positions it has been found necessary to attach the handle 3 to the hammer head in such a manner as 15 to admit of varying the relative position of the handle, thereby enabling the tool to be used in close quarters and in places difficult of access. For this purpose a connection 11 is fitted in an opening 12 formed transversely 20 in the hammer head, said opening being enlarged at one end, as indicated at 13, to form a flaring wall for an enlarged portion 14 of the connection 11 to engage by a wedging action. The connection 11 is in the 25 nature of a stem or rod which is externally threaded to fit within the opening 12 which is correspondingly threaded. The end of the connection to which the handle 3 is attached is split or forked, the fork members 30 having their inner sides corrugated or roughened to match correspondingly corrugated or roughened sides at the attaching end of the handle 3. A bolt 15 passes through registering openings formed in the 35 forked end of the connection 11 and in the attaching end of the handle 3. The handle pivots on the bolt or fastening 15 and the latter may be used to draw the fork members of the connection together so as to cause the 40 corrugated faces or sides to engage and thereby hold the handle in the adjusted position. The fork members may be further drawn together and held in fixed position by the flaring portion 14 at the base of the 45 fork members engaging and riding upon the flaring wall 13 of the enlarged end por-

tion of the transverse opening 12. The connection 11 may be turned by fitting a wrench or other suitable tool thereto. By backing the connection 11 and loosening the bolt or 50 fastening 15 the fork members spread by a spring action, thereby disengaging their corrugated faces from the corrugated faces of the attaching end of the handle so that the latter may be turned to any relative angular position, after which the same is made 55 secure by tightening the fastening 15 and screwing the connection 11 into the threaded opening 12.

Having thus described the invention what 60 is claimed as new, is:—

1. The herein described tool comprising a hammer head provided with a handle and having parallel openings, a chisel having spaced stems arranged to operate in the 65 openings of the hammer head, springs mounted upon said stems within the openings of the hammer head, and nuts threaded to the stems for confining the springs thereon.

2. In a tool of the character described, the 70 combination of a hammer head provided with a chisel and having a transverse opening which is flared at one end, a connection fitted in the transverse opening and having one end forked and provided at the base of 75 the fork with a flared portion to engage the flared end of the transverse opening of the hammer head, a handle secured between the fork members of the connection, and means for drawing said connection into the open- 80 ing of the hammer head whereby the tapered portion rides upon the flared portion of the opening and thereby causes the fork members of the connection to grip the attaching end of the handle. 85

In testimony whereof I affix my signature in presence of two witnesses.

EDGAR J. CHANDLER.
